DESIGN FOR A BUTTON OR SIMILAR ARTICLE

Harry Newman, Newark, N. J., assignor to Button Corporation of America, Newark, N. J., a corporation of New Jersey

Application August 30, 1938, Serial No. 79,644

Term of patent 7 years

To all whom it may concern:

Be it known that I, Harry Newman, a citizen of the United States, and a resident of the city of Newark, in the county of Essex and State of New Jersey, have invented a new, original, and ornamental Design for a Button or Similar Article, of which the following is a specification, reference being had to the accompanying drawing, forming a part thereof.

Fig. 1 is a face view of a button or similar article showing my new design;

Fig. 2 is a view of the back of the button; and

Fig. 3 is a sectional view taken along the line 3—3 of Fig. 1.

The dominant features of my design consist in the ornamentation appearing on the front and rear sides of a button or similar article.

I claim:

The ornamental design for a button or similar article, substantially as shown and described.

HARRY NEWMAN.
